UNITED STATES PATENT OFFICE.

CHARLES J. SHELVERTON, OF AUSTELL, GEORGIA.

DESIGN FOR A TYPE-CABINET.

SPECIFICATION forming part of Design No. 28,203, dated January 18, 1898.

Application filed December 7, 1897. Serial No. 661,113. Term of patent 7 years.

To all whom it may concern:

Be it known that I, CHARLES J. SHELVERTON, a citizen of the United States, residing at Austell, in the county of Cobb and State of Georgia, have invented a new and original Design for a Type-Cabinet, of which the following is a specification.

The material features of my design for a type-cabinet are an oblong base having in one of its faces a series of ledges or steps occupying different horizontal and vertical planes, a series of circular pockets in each step or ledge, and end pieces having their curved front edges extended beyond the ledges or steps of said base.

In the accompanying drawings, Figure 1 is a perspective view of a type-cabinet, showing my design. Fig. 2 is an end elevation thereof. Fig. 3 is a vertical cross-sectional view.

As shown by the accompanying drawings, my design for a type-cabinet consists of a substantially oblong base 1, having in its exposed face a series of horizontal ledges 2, 3, 4, and 5, arranged one in rear and above the other in step-like order. The front face 6 of the base below the lowermost step 2 is vertical and imperforate. The ledges are in horizontal parallel planes, and the faces of the base between the ledges or steps are vertical. The ledges or steps extend throughout the length of the base. In cross-section the base is chambered or hollowed at 7, and on the rear side of the base is the vertical back wall 8.

In each horizontal ledge or step is a series

of circular pockets 9, which are spaced at suitable intervals throughout the length of the ledge or step and which open through the upper exposed face of the step. As there are a series of these steps and as each step has 40 a series of pockets, my newly-designed base is thus provided with a plurality of series of pockets which open through the exposed upper faces of the steps or ledges.

The flat end pieces 10 are applied to the 45 ends of the base and the straight horizontal and vertical edges of each end piece are flush with the bottom and rear wall of the base. The upper edge of the end piece is curved downward and forward from the rear of the 50 base to the front thereof, and such curved edge of said end piece projects above the steps or ledges of the base. The curved edges of the flat end pieces are substantially equidistant from the front angles or corners 55 of the series of ledges or steps except at the lower step or ledge, at which point the edges of the end pieces are flush with the angle or corner of the step 2 and the front face 6 of the base. 60

What I claim is—

The design for a type-cabinet herein shown and described.

In testimony that I claim the foregoing as my own I have hereto affixed my signature in 65 the presence of two witnesses.

CHARLES J. SHELVERTON.
